UNITED STATES PATENT OFFICE

LEO RANNEY, OF GREENWICH, CONNECTICUT, ASSIGNOR TO STANDARD DEVELOPMENT COMPANY, A CORPORATION OF DELAWARE

RECOVERY OF OIL FROM THE EARTH BY MINING OPERATIONS

Application filed August 5, 1926. Serial No. 127,233.

This invention relates to the recovery of oil from the earth by mining operations including the formation of a working area, adjacent to but spaced from an oil-bearing stratum or oil sand, from which area expulsive forces may be applied to drive the oil to a discharge opening. The invention comprises especially the application of expulsive forces from a zone of attack in such a manner as to 10 converge toward the center of the tract being worked. Wells are sunk from the earth surface to receive the expelled oil.

The invention will be fully understood from the following description, taken in connection with the accompanying drawings, in which

Fig. 1 is a fragmentary diagrammatic vertical section through an installation in which a shaft and mine gallery or tunnel are provided;

Fig. 2 is a plan view of an oil recovery system, the plane of the view being taken on line II-II, Fig. 1;

Fig. 3 is a partial vertical section through an alternative form of installation comprising chambers formed in the oil sand;

Fig. 4 is a complete plan view corresponding to Fig. 3; and

Fig. 5 is a vertical section showing the method of tapping gas sands to secure a supply of expulsion agent.

Referring to Figs. 1 and 2, reference numeral 1 denotes a mine shaft passing through an upper cap-rock 2 and an oil sand 3. The shaft is sealed from the oil sand by a concrete wall 4, or other suitable means. A mine gallery or tunnel 5 is driven from the bottom of the shaft 1 through the lower cap-rock 6, or other impervious stratum underlying the oil sand. The gallery is preferably extended along each edge of the track to be worked, for instance a forty-acre unit, in the general manner shown in Fig. 2. A suitable number of more or less centrally located wells, for instance the five wells designated 7, 8, 9, 10, and 11, are drilled from the earth surface to tap the oil sand.

A pipe 12 is laid horizontally throughout the gallery 5 and has branch nipples 13 sealed 50 in the lower cap-rock 6 by sealing material

14. Each of the nipples has a valve 15 of the gate type. Holes or mine wells are drilled through the nipples into the oil sand, the drill being inserted through the outer end of the cross fitting 16 provided at the base of each nipple. In my Patent No. 1,684,236 granted June 28, 1927, of which the present application is a continuation in part, I have described in detail the formation and operation of mine wells of the type referred to. 55

A suction pump 17 is connected to the pipe 12 and forwards the fluid entering that pipe through a connecting pipe 18 to the surface storage tank 19. A pipe 20, connected to a source of the expulsion agent (gas, air, 60 water, etc.), is connected to the pipe 18. A valved by-pass 21 is provided for carrying the expulsion agent around the suction pump 17. 65

In the operation of the installation described I prefer to proceed as follows: First, strong suction is applied to the pipe 12 and the nipples connected to it. In this way there is soon formed an unexcavated drainage tunnel (area from which oil has been largely exhausted) extending entirely around the tract being worked. Since the mine wells tap the bottom of the sand at numerous closely spaced points, the evacuation of oil is rapid and quite complete for a considerable distance from the gallery. The oil collected is forwarded to the storage tank 19. The flow of oil from the mine wells may be controlled, and heat may be applied, as described in Serial No. 14,448 above referred to, but in most fields this expedient will not be necessary for the purposes of the present invention. 75 80 85

When the unexcavated drainage tunnel has been established around the tract to be worked, an expulsion agent, for example air or a special gas which breaks the surface tension of oil adhering to the sand grains is forced through pipes 20, 18 and 12 and nipples 13 into the oil sand 3. A wall of air is thus formed around the tract, enclosing the oil and forcing it along lines converging towards the center. The nipples should be placed sufficiently close together to ensure that the air or gas injected from each over- 90 95 100

laps with that injected through the adjacent nipples, so that a continuous or substantially continuous air layer is formed. Escape of oil to surrounding tracts is substantially prevented

5 by the barrier of air interposed between the tract being worked and those adjacent to it. Differences in porosity of the sand at various points of the tract may require that valves in different mine wells be 10 partially closed to admit less air. This gives means by which to control the direction of the wave of air or gas in the sand, so that it may reach all points.

15 During the forcing in of the air some oil is likely to drain into the mine wells. This oil may be collected in one or more tanks 20' and subsequently forwarded to the main collecting tank 19. Separate pipe systems for withdrawing oil and introducing the expulsion agent may be provided, but this is generally unnecessary.

20 The four outer wells, 7, 8, 9 and 10, first receive the oil as it is forced inwardly from the boundaries of the tract. When air begins to be discharged from these wells they 25 are closed and the central well 11 is used for the withdrawal of oil. However, variations in the porosity of the sand might alter the arrangement of producing wells.

30 By applying the expulsion agent in the manner described I secure a very complete recovery of the oil. The expulsion agent operates upon a body of oil which is continuously becoming denser and which is continuously filling any voided streaks of sand and, therefore, is effectively displaced by the agent. This method eliminates any by-passing of oil, such as occurs when applying air on a lengthening or a stationary line of attack. 35

40 I operate with a constantly shortening line of attack upon the oil sand.

45 For best results the mine wells should be drilled entirely around the producing area, but some of the advantages of the invention may be obtained with other arrangements. For example, an expulsion agent introduced through mine wells on two or three sides of the area will permit a high recovery of oil from the sand.

50 According to Figs. 3 and 4, there is illustrated a mine gallery or a tunnel 21' of the type above referred to, connected with a chamber 22 formed in the oil sand itself. The chamber is walled with concrete or the like 55 23 so as to seal it from the oil sand. Holes 24 are drilled from the chamber in a generally horizontal direction along two or more sides of the tract to be worked. I prefer to form one of the chambers at each of the four corners of the tract, as shown in Fig. 4, the holes 24 extending from each chamber approximately half-way along the sides of the tract.

60 The holes 24 are conveniently formed by inserting a drill through the nipple 25 sealed

in the wall of the chamber 22. The nipple is connected with a fitting 26, having a gate valve 27 and end closure 28 adapted to permit passage of the drill. Additional sections of drill stem are added as the drill penetrates the sand, and it is practical to form horizontal openings of the required length. After removal of the drill the expulsion agent is supplied through pipes 29 and 30 to the header 31, from which it passes into the nipples and thence into the open holes extending through the sand. Suction may be preliminarily applied to pipe 29 to withdraw oil draining into the open holes 24.

65 Mine wells may be provided in the tunnel if desired. Where it is more economical to sink shafts for the construction of the several chambers the gallery may be omitted. In my application Serial No. 100,531, filed April 8, 1926, a general method of operating 70 with the use of chambers in the sand is described and claimed. The utilization of this process herein is in the supplying of an expulsion agent continuously along the bottom of the sand and with a continuously shortening line of attack upon the oil sand.

75 Test pipes 32 (Fig. 1), each carrying a fluid gauge 33 and a pressure gauge 34, are preferably provided at numerous levels in the sand. With the aid of information obtained from these test pipes and their attached measuring instruments the operation of the system can be varied, as may be required by the particular conditions encountered. For example, it may be that the expulsion agent from one side of the tract encounters less permeable material than exists on the other sides, and, therefore, is moving relatively slowly outward from the nipples. This will be indicated by the pressure gauges 80 on the first mentioned side reading higher than those on the other sides. The pressure under which the expulsion agent is supplied will be modified so as to equalize this difference and secure a substantially uniform 85 advance toward the center of the tract. The amount of pressure necessary will vary greatly with conditions. A pressure of 100 lbs. per square inch maintained adjacent the gallery will be adequate for the average oil sand. Test pipes should be placed at least 90 every 300 or 400 yards throughout the extent of the galleries. The use of these pipes is described and claimed in my application Serial No. 116,857 filed June 18, 1926.

95 While air has been chiefly mentioned as an expulsion agent, others may be more suitable under certain conditions. Gas and water may be conveniently used. Where one or more gas sands are adjacent the oil sand, it is convenient to secure the gas in the general manner shown in Fig. 5. In this figure a gas line 35 taps the gas sand 36 and is connected to a pipe 37 which delivers into the nipples 100 38. Assuming that there is also an under-

lying gas sand 39, this may be connected with the pipe 37 by a pipe 40. Valves 41 and 41' and pressure gauges 42 and 42' are provided on the gas lines 35 and 40, respectively.

5 It is sometimes desirable to ream out an opening about the inlet ends of the gas lines, as shown at 43 and 43', Fig. 5. A better flow of gas is obtained in this way. Flow of oil may be expedited also by reaming chambers 10 44 at the inlet of each mine well.

I prefer to operate from beneath the oil sand in most cases, but where difficulty of 15 tunneling or other causes makes this inadvisable, my method can be operated from a working area adjacent the upper surface of the oil sand. The preliminary formation of an unexcavated drainage tunnel is generally desirable, since a substantial amount of oil can be recovered as an incident to this 20 operation. However, the expulsion agent may be forced into the sand without preliminary withdrawal of oil, and all the oil may be driven to the central collecting openings or oil wells.

25 It will be understood that the number of mine wells may be varied greatly, the only requirement being that they be sufficiently close together to permit the formation of an effective wall of the expulsion agent introduced through them. In working a square forty-acre tract of a thick, highly consolidated oil sand, I prefer to make about 132 mine wells on each side, the wells usually being equally spaced along the sides.

35 Various changes and alternative arrangements may be made within the scope of the appended claims, in which it is my intention to claim all novelty inherent in the invention, as broadly as the prior art permits.

40 I claim:

1. In the recovery of oil from an oil-bearing stratum, the improvement which comprises forming a mine gallery along the margin of the tract to be worked, the gallery being adjacent said stratum but spaced therefrom by material substantially impervious to fluid, tapping said stratum from the gallery by a large number of closely spaced openings, drilling a surface well to the stratum within 45 the area defined by the gallery, and introducing a fluid oil-expelling agent through said closely spaced openings, thereby forming a fluid barrier moving inwardly from the margin of the tract to force the oil therein through the surface well.

50 2. Method of recovering oil from a selected area of an oil-bearing stratum, comprising forming a mine gallery adjacent to but below or above said area, said gallery extending 55 about the margin of the area, forming a large number of closely spaced openings from the gallery into the oil-bearing stratum, drilling a surface well within said area, withdrawing oil from said openings to form an unexcavated drainage tunnel, then forcing an ex-

pulsion agent into the stratum through the openings, whereby the oil is forced toward the center of the area, and withdrawing the oil from the surface well.

3. Method of working a selected area of an oil sand, comprising forming from a mine gallery about the margin of said area a large number of closely spaced openings, drilling a well from the earth surface to tap a central portion of said area, and forcing an oil-expelling agent into the sand from the said openings, whereby the oil is forced toward the center of said area, and withdrawing the oil from said well.

4. Method according to claim 3, in which the oil-expelling agent is gas obtained from a stratum adjacent the oil sand.

5. Method according to claim 3, in which the oil-expelling agent is supplied under pressure regulated in accordance with conditions in the sand, as indicated by test devices inserted therein.

LEO RANNEY.
